UNITED STATES PATENT OFFICE.

CHARLES E. RANDALL, OF STAPLETON, NEW YORK, ASSIGNOR TO HILBORN-HAM-BURGER, INC., OF NEW YORK, N. Y., A CORPORATION OF NEW YORK.

SHIELD.

Application filed April 6, 1926. Serial No. 100,118.

This invention relates to shields for use in holding buttons, buckles, clasps or other metallic parts of the regulation equipment of Army, Navy and Marine uniforms while such parts are being polished and for protecting the cloth and other parts of the uniform during the polishing operation.

As is well known, the regulation equipment of Army, Navy and Marine uniforms includes many metal buttons, buckles and clasps that require frequent polishing. As a matter of fact, several hours a week are required to keep the metal parts polished in accordance with service regulations.

15 This invention has for its salient object to provide a shield or protecting device of the character described so constructed that all of the metallic parts of the uniform equipment can be polished easily and expeditiously without soiling the uniform, garment or other parts of the equipment.

20 Further objects of the invention will appear from the following specification taken in connection with the drawings, which form 25 a part of this application, and in which

Fig. 1 is a plan view of a shield constructed in accordance with the invention;

Fig. 2 is a perspective view of the shield or protector shown in Fig. 1; and

30 Fig. 3 is a transverse sectional elevation taken substantially on line 3—3 of Fig. 2.

The invention briefly described consists of a plate having a plurality of notches or slots formed at the edges thereof and a plurality of openings extending therethrough. The notches and openings are so arranged that the notches and openings will coact with every metallic part of the regulation equipment of the Army, Navy and Marine uniforms so that these parts can be held in position while being polished and the plate will protect the cloth or other parts of the uniform. The notches along one edge of the plate are so arranged as to coact with all of the buttons on the front of the uniform and a sliding bar or member is mounted on the plate and is adapted to secure the buttons to the plate and hold them in position as they are being polished. Further details of the invention will appear from the following description.

35 The shield or protector consists of a plate 10 preferably formed of some light metallic material, such as aluminum. The plate 10 has a plurality of notches A, B, C, D and E

formed along one edge thereof and adapted to coact with the buttons on the front of the uniform. It will be understood that the thread which secures the buttons to the uniform, will enter the notches.

In order to securely retain the buttons in position when they are being polished, a slide- 60 able bar or strip 11 is mounted on the plate 10 by means of a pin and slot connection 12, 13. The slideable strip 11 has formed therein 65 notches having portions 15 parallel to the notches A, B, C, D and E and having portions 16 disposed at an angle, such as a right angle, with reference to the portions 15 or notches A, B, C, D and E. When the shield is used to 70 polish the buttons, the thread or connecting medium used for securing the buttons to the uniform is placed in the notches A, B, C, D and E and enters the portions 15 of the notches in the slideable strip. The strip will 75 be positioned as shown in Fig. 1 when the buttons are being secured by the shield. After the thread or connecting medium has been placed in the inner ends of the notches, the strip 11 will be moved longitudinally so that 80 the portions 16 of the notches therein will close the notches A, B, C, D and E and will firmly secure the buttons in position for polishing. Thereafter all of the buttons may be 85 polished simultaneously.

Notches F and G are formed in the plate along one end thereof and are adapted to fit the large belt buckle.

Notches H, I and J along the edge opposite the notches A, B, C, D and E are adapt- 90 ed to fit the cartridge belt clasp.

Notches K, L are adapted to fit the small buckles on the cartridge belt.

It will be noted that the plate 10 has also 95 formed therein a plurality of openings. The small opening M fits the eyelets on the cartridge belt. Opening N fits the insignia on the cartridge belt pack. Opening O fits the clasp on the pocket of the cartridge belt. Opening P fits the clasp on the first aid pack. 100

From the foregoing description it will be seen that the single plate 10 is provided with means for securing and holding all of the various metallic parts of the regulation equipment of Army, Navy, and Marine uniforms. 105 The device it will be observed is a unitary structure wherein certain metallic parts of the uniform may be placed in the slots A, B, C and the slide utilized to hold same in place while they are being polished, or if de- 110

sired, and quite frequently it is desirable, the openings N, O or P, as well as M of the slots H, I, J, K, or L are used at the same time as the slots A, B &c., so that various different 5 metallic parts of the uniform may be cleaned and polished at one and the same time. The use of this plate will greatly facilitate the polishing of these metallic parts and will very materially reduce the amount of time required to polish the buttons, buckles and 10 clasps of the equipment. Furthermore, the cloth or other parts of the equipment are protected from soiling.

Although one specific embodiment of the 15 invention has been particularly shown and described, it will be understood that the invention is capable of modification and that changes in the construction and in the arrangement of the various cooperating parts 20 may be made without departing from the spirit or scope of the invention, as expressed in the following claims.

What I claim is:

1. A shield and holding device consisting 25 of a sheet of material having a plurality of notches along an edge thereof and a plate slidably mounted on said sheet and having angularly formed notches, spaced apart distances corresponding to the spacing of the 30 notches in said sheet, said angular notches having portions adapted to aline with the other notches and having portions disposed at an angle thereto.

2. A device of the character described 35 consisting of a plate having a plurality of parallel spaced notches extending inwardly from the edge thereof and a strip slidably mounted on

said plate adjacent said notches and having angularly formed notches spaced apart corresponding to the spacing of the notches in 40 said plate, said angular notches being so arranged that in one position of the strip, portions of the strip notches will aline with the plate notches, said strip being so arranged that it may be slid on the plate to 45 position said portions of the angular notches out of alinement with the plate notches, but with the other portion of the angular notches overlapping the plate notches.

3. A device of the character described consisting of a plate of relatively thin, stiff material having a plurality of parallel spaced notches along the edges thereof arranged to co-act with certain metallic parts of uniform equipment, said plate also having a plurality of openings therein so dimensioned so as to co-act with other metallic parts of such equipment and a strip slidably mounted on said plate adjacent said notches and having angularly formed notches spaced apart corresponding to the spacing of the notches in said plate, said angular notches being so arranged that in one position of the strip portions of the strip notches will aline with the plate notches, said strip being so arranged that it may be slid on the plate to position said portions of the angular notches out of alinement with the plate notches but with the other portions of the angular notches overlapping the plate notches.

In witness whereof, I have hereunto set my hand this 24th day of March, 1926.

CHARLES E. RANDALL.
